UNITED STATES PATENT OFFICE.

PETER KUZMJAK, OF NEW YORK, N. Y.

DESIGN FOR A SOCIETY MEMBERSHIP PIN.

Application filed February 28, 1922. Serial No. 948. Term of patent 7 years.

To all whom it may concern:

Be it known that I, PETER KUZMJAK, a citizen of Czechoslovakia, residing at New York, in the county of New York and State of New York, have invented a new, original, and ornamental Design for Society Membership Pin, of which the following is a specification, reference being had to the accompanying drawing, forming part thereof.

The figure is a front elevational view of a society membership pin, showing my new design.

I claim:—

The ornamental design for a society membership pin, as shown.

PETER KUZMJAK.

Witnesses:

JOHN HAVAS,
JOHN GOLIK.
